SOLE SHAPING MACHINE

James S. Brown, Lynn, Mass., assignor to Shoe
City Machine Company, Inc., Lynn, Mass., a
corporation of Massachusetts

Application August 12, 1935, Serial No. 35,735

13 Claims.

(Cl. 12—21)

This invention relates to machines for shaping soles for shoes and more particularly, but not exclusively, for fashioning soles to the correct shape for bottoming women's shoes having Louis 5 heels. This work is generally called sole "molding" and will be so referred to herein although, as will be understood from the following description of the machine and of the method used for fashioning a flat sole into one adapted to high 10 shank and high heel work, this invention does not rely upon heavy compression as used in direct pressure molding but rather alters the shape of the flat sole by a progressive re-forming of the leather or other stock of the sole. Shaping is 15 required in women's work at the shank of the sole but if desired this invention may be utilized for shaping the forepart of the sole to fit lasts having rounded bottoms. The machine has a wide range for shank-shaping soles for various 20 types of shoes, particularly the soles of cemented or Compo shoes and in this connection, which is of especial importance in the industry, it enables Del Mac and like process soles to be effectively shank-shaped without injury to or distortion of the specially formed forepart on soles 25 processed in this way.

In high shank and high heel work the sole should be provided with a comparatively sharp upward break approximately at the extreme ball 30 line and with an arched shank rearward therefrom, the arch finally merging into the flat stock forward of the heel seat. The high lines of the reformed shank stock form approximately a Y with its stem lying centrally along the shank 35 and its branched arms defining a more or less rounded rear edge of the forepart or tread surface of the sole. The machine may be used to shape shanks to any style of last, even to produce the extremely sharp breaks known as a "cottage" 40 shank. It will be understood that the sole should first be tempered before being deformed. The tempering found to be most efficient for the work of this invention comprises a quick dipping of the sole which is then set for a light mull. 45 The molding mull thus acquired softens the stock sufficiently to permit the shank to be progressively shaped as hereinafter described, particularly to take the sharper break at the rear of the forepart and then to retain all characteristics of 50 the new shape even after the natural spring back of the deformed parts upon drying the sole. The principal object of this invention is to provide soles with a shank shape as above described for correctly fitting the bottoms of lasts for shoes 55 of the kind or style having a pronounced upward

curve between the forepart and the heel seat, and to the accomplishment of this object and such others as may hereinafter appear, as will readily be understood by those skilled in the art, the invention comprises the features and combinations 5 of parts and processes of manufacture herein-after described in detail and then claimed.

The nature and purposes of the invention will be understood from a description of the preferred embodiment of the sole shaping machine illustrated in the accompanying drawings, in which:

Figure 1 is a view of the machine in rear elevation. This view shows the rotation of the molding couples as having been stopped prior to the ejection of the shaped soles to present the inset male 15 and female molds in full view.

Fig. 2 is a view of the head of the machine in side elevation, with the rear roll bearing housing removed to present a full view of the molding couples and sole feeding mechanism. In this view 20 the machine is at rest and a sole is shown in position between the shaping molds;

Fig. 3 is a view, in plan, of the head as shown in Fig. 2 but showing both roll bearing housings and having the upper rolls of the two sole molding couples removed to present a full view of the heel centering gages;

Figs. 4 and 5 are views, in side elevation, of a sole molding couple with a sole passing therethrough at two stages of the shaping operation. 30 In Fig. 4 the molds are just beginning to engage the sole and its feed to the molding couple is still under control of the toe gage. In Fig. 5 the molds are just completing the Y-break at the extreme ball and the molding couple has 35 taken control of the feed of the sole away from the toe gage;

Fig. 6 is a view, in elevation, of the toe gages, showing the center block broken away to expose the connection to the feed slide; 40

Fig. 7 is a cross-sectional view through the center block of the toe gages showing the manner of their adjustment;

Fig. 8 is a fragmentary view of a portion of a 45 recess mold at the time of laterally arching the shank about the shank ridge of a saddle mold. This is a front view of the molds at a time in the cycle intermediate the showings in Figs. 4 and 5 and discloses how the lips of the recess mold 50 merely bend or set the margins of the shank down about the saddle ridges without compressing the stock;

Fig. 9 is a cross-sectional view through the shank of a sole that has been skived at its mar- 55

gins emphasizing the shank stiffener seat formed by the co-acting recess and saddle molds;

Figs. 10 and 10a are views in plan and in side elevation, respectively, of a sole after its shank has been molded. The dotted lines on Fig. 10 indicate the shape of the shank ridge and forwardly branching ridges of the saddle mold over which the stock is deformed by the recess mold to produce an upward Y-break at the rear end of the forepart;

Fig. 11 is a view, in plan, of two superposed soles, the upper sole being one size smaller than the lower sole, showing the half-size variation at the toe and heel but no variation in contour at the waist in the region of the complete ball and extreme ball; and

Fig. 12 is a view, in side elevation, of a high arch shoe with a Louis heel and bottomed with a shank shaped sole made according to this invention to show the flattening of the overmolded arch of the shank that takes place during the sole laying operation.

Before explaining the present invention in detail, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

In the embodiment of the invention illustrated in the drawings the rolling sole shaping molds of the machine are mounted in a head 10 bolted on legs 14 at a convenient height for positioning soles on a table 15 bolted to the head. There are preferably a pair of sole molding couples mounted in the head so that a pair of soles may be shaped simultaneously thus doubling the output of the machine, but it will be understood that a twin machine is not essential to practising the invention.

The upper or female mold rolls 16 and 16' of the two couples are mounted on a driven shaft 18 journaled in bearings 19 slide vertically in side housings 20 under the yielding pressure of comparatively light coiled springs 22 (about 75 pounds pressure has been found to be efficient) confined between the bearings and a cap plate 24. The lower or male mould rolls 26 and 26' of the two couples are mounted on a driving shaft 28 journaled in fixed bearings 29 within the housings 20. The driving shaft 28 carries a gear 30 and the driven shaft 18 carries a gear 31 of the same size so that the upper and lower mold rolls of each couple are driven in opposite directions at the same rate of speed.

The driving mechanism comprises a master shaft 32 at the lower part of the frame having, as illustrated, fast and loose pulleys 33 and 34 at one end for a belt drive, but obviously any suitable motor drive may be substituted. The other end of the shaft 32 carries a bevel gear 35 meshing with a bevel gear 36 on a vertical intermediate shaft 37 journaled in bearings projecting from the frame as shown. The upper end of the shaft 37 carries a bevel gear 38 meshing with a bevel gear 39 loose on a projecting end of the driving shaft 28 of the sole molding couples. Intermediate the loose bevel gear 39 and the adja-

cent housing 20 the driving shaft carries the fast member 40 of a one-revolution clutch of any suitable type. As here shown the fast clutch member 40 is continually pressed toward the gear 39, which forms the loose member of the clutch, by a coiled spring 41. The clutch is thrown into operation to turn the molding couples through one revolution by depressing a treadle 42 connected by a rod 43 to the cam latch usual in this type of clutch. After one revolution the clutch is thrown out automatically and the molding couples are always brought to rest with their male and female molds in the same relative angular position as that from which they started their rotation.

Remembering that this is a sole shaping and not a sole compressing operation, that is, the shank of the sole is deformed by a bending and setting of its stock while in a milled condition, the function of the female mold is to progressively press the stock down upon and cause it to take the shape of the male or saddle mold. Thus it is important, in such a progressive shaping operation by a rolling couple, to initially position the sole relatively to the molds so that the upward break will be made uniformly at the rear boundary, called the extreme ball, of the forepart or tread surface of the sole, whatever its size. Also of importance is insurance that the shank will be centered on the saddle mold during the complete deforming operation. To this end a sole feeding mechanism is provided that co-operates with the molding couple to control the advance of the sole until it is certain that the molds will complete their deforming operation without danger of the sole tipping or shifting from its centered position.

It will be seen from the shaped sole illustrated by Fig. 10 and from the showing of the male and female molds that the male or saddle mold presents a ridge having a rounded top about which the shank is laterally arched, which ridge terminates forward in a Y-ridge for breaking the shank upward from the forepart at the extreme ball line or rear boundary of the tread face of the sole; and that the female or recess mold presents a groove having a concaved bottom the side lips of which co-act with the saddle mold ridge to bend down the margins of the shank stock about said ridge, and said groove terminating in a laterally branched recess complementary to the Y-ridge of the saddle for forming the break at the rear of the forepart.

The twin molding couples are alike so that the description now following may refer to a single molding couple. Each female mold 48 and each male mold 50 is formed separately of suitable metal and provides a removable insert on the upper and lower rolls respectively of the molding couple by having its flat base plate secured in a longitudinal groove cut in the peripheral face 60 of the roll as shown best in Figs. 2, 4 and 5. Each molding roll of a couple has a segment removed slightly to the rear of its inset mold providing upper and lower flats 52 and 54 which, when opposed to each other as when the machine is at rest (Fig. 2), form a space between the rolls into which the heel of a sole may be slipped in positioning it for the shank shaping operation. Thus the short peripheral surfaces intermediate the rear edge of a roll flat and the forward edge of a mold base plate constitute the first areas to grip a sole on starting the couple in operation. The flat 52 is an unobstructed plane surface but at the center of the flat 54 there is provided a well known type of sole centering device consisting of 75

a pair of arms 55 each pivotally mounted but geared together at their pivoted ends to move uniformly toward and from each other with a connecting spring to draw them yieldingly inward. Each arm carries a small heel gage roll 57 at its free end and the usual stop is provided to limit inward movement and hold the gage rolls such a distance apart as to permit setting the narrowest heel end therebetween. When the machine is at rest the flat 54 on the lower roll of the molding couple is preferably, but not necessarily, in the plane of the table 15.

In order that the sole may be held on the table 15 with the median line of its shank in the exact plane of the median lines of the inset molds, the heel gage is supplemented by a V-block toe gage 56 which is adjustable toward and from the molding couple for variations in size and laterally across the table for variations in style, mainly to adjust for differences in the swing of the last which throws the forepart at a greater or less angle to the median line of the shank.

For a twin machine there are two toe gages 56 and 56' (Fig. 3) having inwardly extending racks 58 and 58' respectively which overlap and ride in the open channel of a center block 59. The rear wall of the channel is formed by a bar 60 screwed to the center block and extending laterally for some distance beyond each end thereof. The table has a central longitudinal slot 61, and a short guide plate 62, secured to the bottom of the center block, seats in this slot. Also seated in the slot, from below (Figs. 6 and 7), is a slotted feed slide 63. A bore centrally of the center block receives a vertical pin 64 having a flattened head within the slot of the slide 63 to prevent rotation and a threaded upper end which receives a wing or other releasable lock nut 65. Intermediate the wing nut and resting on the top of the rack channel is a loose adjusting nut 66 having a small gear 67 fast at its lower face which seats in the channel between and meshes with the two toe gage racks.

For shaping a pair of soles for a straight last as illustrated in Fig. 2 the toe gages are in alignment with the inset molds but for shaping a pair of soles for a swing last the toe gages would have to be moved nearer together. To accomplish this the wing nut 65 is loosened and the adjusting nut 66 is rotated in a direction to cause the racks 58 and 58' to draw the toe gages closer together along the bar 60 as a guide until the two gages are in position for engaging the toes of the soles while still maintaining the median line of the shank in direct alignment with the inset molds. Thereupon the wing nut is tightened and the toe gages are again clamped to the feed slide 63.

To adjust the toe gages for different sizes of soles the wing nut 65 is loosened as before and the center block is moved toward or from the molding couples in the slot of the feed slide 63. The bar 60 has a pointer at one end which indexes on a size scale 68 screwed to the table 15. This will be referred to again later.

An eccentric 70 (Figs. 2, 4 and 5) is mounted on the driving shaft 28, conveniently between the two molding couples in this twin machine, in line with the table slot 61. The eccentric strap 72 has a rearwardly extending pitman 74 pivotally connected to a lever 76 pivoted by its lower end to the machine frame. The upper end of the lever 76 is, in turn, pivotally connected to the forward end of a link 78, the rear end of which is pivotally connected to an ear depending from the feed slide 63 supporting the toe gages. Rota-

tion of the eccentric causes the slide to reciprocate once in the slot 61 for each cycle of operations of the machine.

It is not necessary to change the inset molds when the size of the sole to be shaped is changed but it is highly important that the starting point of the shank shaping operation on the sole be changed as the size changes to insure that the finish point or upward Y-break will be formed on soles of all sizes at the extreme ball or rear boundary of the forepart. The Y-ridge at the peak of the saddle mold and the complementary spread at the following end of the recess mold are wide enough to care for all widths of soles so that an adjustment for length makes the machine universal. Remembering that the curvature at the center ball and extreme ball of a series of soles of the same width is precisely the same on all sizes and that only one-half of the increase in length comes at the forepart or between the Y-break and the toe (see diagram of Fig. 11) it will be understood that it is necessary to move the toe gages back only one-half size for each full size change in soles to be shaped in order to insure that the extreme ball of the sole, whatever its size, will always be at the same distance from the molding couple before the cycle of operation starts. Thus for each variation of a single size the heel end of the sole will project one-half size further into the heel centering gage and the molds will start their shaping operation one-half size further forward on the shank, but will uniformly complete their shaping operation with the Y-break forming the rear boundary of the forepart or at the extreme ball.

Describing now a cycle of operations; at the time the sole is positioned the saddle and recess molds are in the positions shown in Fig. 2, the roll flats 52 and 54 are opposite each other and the eccentric 70 has turned through about 30° of its forward stroke so that the feed slide 63 will be advanced by the faster portion of its stroke immediately the clutch is thrown in. It will be observed here that the pitman 74 is adjustable so that the pointer on the rod 60 may be calibrated with the scale. The toe gage having been set for the size and swing of the sole to be shaped the heel end of the sole is slipped between the flats which provide a space to receive it and is centered relatively to the molds by the yielding heel gage rolls 57 on the lower flat 54. The sole at the same time is drawn back seating its toe within the V of the previously adjusted toe gage 56 thus determining alignment of the shank with the ridge of the saddle mold 50. This setting also presents the sole, whatever its size, in a feed position with relation to the length of the molds such that the Y-break will necessarily be formed at the rear boundary of the forepart tread face.

The clutch is thrown in and the action of the machine during the single revolution of the sole molding couple is as follows. The heel gage draws away from the sole when the rolls begin to rotate but during this period the sole is positively advanced in time with the advancing molds by the driven shaft 18 lift slightly against the springs 22 from their seatings on the bearings of the driving shaft 28 thus holding the sole firmly, but without compression, in its shank-aligned position relative to the molds. Immediately there-

after the sole is gripped, under pressure of the springs 22, adjacent its breast line by the forward ends of the two molds, the lips of the recess mold thereafter closing down progressively upon the 5 shank ridge of the saddle mold, first bending the margins of the shank down gradually where the saddle ridge is widest and then so sharply downward over the saddle ridge as to produce an overmolded arched shank that will be retained even 10 after the stock has sprung back upon drying. Fig. 4 shows that the position of the sole during this period is still under control of the advancing toe gage. If the toe were released while the shank is being laterally arched any difference in the 15 condition of the stock at one side or the other of the shank, or some other difficulty that would require more pressure on one side than the other, tends to twist or tip the sole from its true relation to the molds, but by retaining the toe in its V- 20 gage a shift or misplacement of the sole during this period is prevented. The positive control of the position of the sole is retained until the shaping has progressed so far that the sole cannot shift between the molds. The eccentric motion 25 slows up the feeding speed just prior to the setting of the sole stock between the branched ridges and recesses of the molds for producing the terminating Y-break so that at the time this break is made the molds have drawn the sole away from 30 its toe gage which is then about to start its back stroke as shown in Fig. 5. Therefore, for the latter portion of the molding operation the sole is carried through the machine by the grip of the molding couple.

35 Beyond the two complemental molds the rolls of the couple may have cylindrical surfaces where the forepart of the sole is to be flat or, as illustrated, they may have convexed and concaved peripheral surfaces to curve the forepart to any degree required for fitting to a rounded last bottom. It 40 is within the scope of this invention to shape these portions of the molding rolls to suit any type of sole to be molded, for example, a sole having a thick center and skived margins at its forepart 45 such as Del Mac process soles can be handled perfectly by increasing the depth of the concavity of the upper roll sufficiently to receive the thick center, relying then upon the grip by the ends of the roll for feeding.

50 While the forepart is riding through the molding couple the eccentric or other cam motion as may be desired causes the toe gage to travel back on the table and finally, when the clutch is disconnected, stop at the point opposite the scale 55 from which it started. The shaped sole is meanwhile dropped from the molding couple into a basket at the rear of the machine. During the whole of the shaping operation the comparatively light pressure under which the recess mold is held, while crowding the stock down and shaping 60 it to the shank ridge and peak of the saddle mold, permits the upper roll to lift whenever it is necessary to ease the sole over a tight place.

65 It will be seen on comparing Fig. 12 with Fig. 10a that the arch of the shank in the shoe is much flatter than the arch as shaped by this invention. As heretofore stated the shank is purposely overmolded first to compensate for the natural spring back of the stock but more especially to 70 insure a fine, tight edged shank on the shoe due to the fact that the overmolded arch of the shank will be flattened against the last at the sole laying operation.

75 Those skilled in the art will recognize many advantages from using the teaching of this in-

vention in the shaping of soles for high heel and high arch work. With merely slight adjustment all lengths and widths can be shaped with a single set of complemental molds. Only a light feeding pressure is employed thus preventing any glazing of the flesh side of sole leather, as occurs with direct pressure sole molding, and eliminating a succeeding operation to prepare the flesh side for cement when the sole is used in compo shoes, a very large field of use for these soles. 10 The molding couple can be adapted to any forepart without damage to the sole as would occur with direct pressure molding. Shaping by progressive pressure is easier on the stock, the shape imparted by the molds is held better and there is less spring back than when direct pressure is used. Speed of operation or output from the machine is greatly in excess of what can be obtained from a direct pressure machine. It has not been possible, by the use of direct pressure, 15 to produce the sharply defined breaks essential to fine shoemaking that can be and are produced by this machine utilizing progressive pressure.

20 The nature and scope of the invention having been indicated and its preferred machine embodiment, operation and use, as well as the underlying essential process of manufacture having been specifically described, what is claimed as new, is:—

25 1. A sole shaping machine having, in combination, two rolls forming a rotary shank molding couple having opposed co-acting male and female shank shaping molds covering a portion of the periphery of each roll adapted to seize a sole 30 inserted between them and to progressively shape its shank portion as the sole passes through said couple, means for rotating the rolls of said couple, and means for so locating the heel end of a sole between said rolls as to cause said molds to seize 35 the sole at such a point relatively to the heel that they will leave the sole at a pre-determined point relatively to the forepart.

40 2. A sole shaping machine having, in combination, a rotary shank molding couple having 45 peripheral male and female molds for gripping and feeding a sole through the rolls of the couple and complementally shaped for forming an arched shank on the sole terminating at its forward end in an upward Y-break, means for rotating the couple, and means for feeding a sole to the rolls of the couple in timed relation to the rotation of said rolls and insuring that the shank is gripped by said molds at a point such that the Y-break is molded at the rear end of 55 the forepart.

3. A sole shaping machine according to claim 2 in which said sole feeding means continues to function until after the molds have gripped the sole and is then discontinued.

4. A sole shaping machine having, in combination, a molding couple consisting of a pair of rolls presenting peripheral male and female shank shaping molds for progressive co-action on a sole passing between them, the peripheral 60 surfaces of said rolls being provided with flats in advance of their molds presenting, when at rest, a space within which the heel end of a sole to be molded may initially be set, and means for rotating said rolls at the same speed and in opposite directions to cause their molds to engage and to progressively shape the shank of the sole as it is fed forward by said rotary molding couple.

5. A machine for shaping soles off the shoe 70 having, in combination, complemental male and 75

female molds each pivotally mounted one opposite the other and shaped for imparting an upward Y-break at the rear of the forepart of the sole and a lateral arching of its shank, means 5 for locating a sole between said molds, and means for rolling said molds in opposite directions to close upon the opposite faces of the sole and to progressively impart the shape of said molds thereto.

10 6. In a machine for shaping soles off the shoe, a pair of co-acting pivotally mounted male and female molds shaped for imparting an upward Y-break at the rear of the forepart of the sole and a lateral arching of its shank, means for 15 causing said molds to progressively engage a sole lengthwise between them to shape its shank and forepart, and heel and toe gages between which the sole is set for initially positioning it relatively to said molds to insure the correct location 20 of said Y-break.

7. In a sole shaping machine, a rotary molding couple, one roll of the couple having a saddle mold at its peripheral surface and the other roll having a complementary recess mold at its peripheral surface for closing on and then leaving the saddle mold during one revolution of the molding couple, said molds being formed and related to progressively laterally arch the shank terminating in an upward Y-break at the rear of the forepart of the sole as it rides through said rotary molding couple.

8. In a sole shaping machine according to claim 7 said saddle mold having a rounded ridge extending from said Y-break rearward and said recess mold having a concave channel co-acting with said saddle ridge, and means for holding the shank upon the saddle ridge under pressure between the molds producing an elongated seat at the center of the shank for receiving a shank 35 stiffener, said recess mold having side lips spaced for bending the margins of the shank stock down at each side of said shank stiffener seat without pressure against the saddle mold.

9. A sole shaping machine comprising a rotary 40 molding couple, a male shaping mold at the per-

ipheral surface of one roll of the couple, a co-acting complementary female shaping mold at the peripheral surface of the other roll of the couple, means carried by one of said rolls for initially positioning the heel end of the sole between said 5 rolls with its median line central with respect to said molds, means for rotating the couple, and means for feeding the sole forward until after it has been gripped by the molds.

10. A sole shaping machine comprising complementary molds for shaping the shank, means intermediate said molds for engaging the heel end of the sole and setting its shank centrally relatively to said shaping means, means for advancing the sole to said shank shaping means, 15 and means for maintaining said shank central relatively to the molds as it is advanced.

11. A sole shaping machine according to claim 10 characterized by a toe gage movable forward with the advancing sole for maintaining said 20 shank central relatively to the shaping molds while said shank is being shaped.

12. A sole shaping machine comprising a rotary molding couple having a male mold on one roll and a female mold on the other, a table for supporting a sole to be shaped, a flat on each roll in advance of its mold, oppositely facing when the machine is at rest and presenting a space at the inner end of the table for receiving the heel end of a sole, a heel centering gage carried by one of 25 30 said flats, a toe gage on the table for insuring operation of the molds on the shank, means for rotating the molding couple to advance its molds upon the sole, and means for advancing the toe gage until the centering may be preserved by the 35 grip of the molds upon the sole.

13. A sole shaping machine comprising a pair of rotary molding couples, a table for supporting a pair of soles for simultaneous shaping by said molding couples, a heel gage associated with each couple for setting the shank of each sole in position for shaping by a molding couple, a pair of toe gages on said table, and means for adjusting 40 said toe gages toward and from each other.

JAMES S. BROWN.
